(57) **CLAIM**

The ornamental design for a swing seat with cupholder, as shown and described.

DESCRIPTION

FIG. 1 is a top perspective view of a swing seat with cupholder;

FIG. 2 is a bottom perspective view thereof;

FIG. 3 is a top plan view thereof;

FIG. 4 is a front elevational view thereof, with a rear elevational view being a mirror image thereof;

FIG. 5 is a left-side elevational view thereof, with a right-side elevational view being a mirror image thereof;

FIG. 6 is a bottom plan view thereof; and,

FIG. 7 is a top perspective view of the swing seat with cupholder shown in its environment.

The broken lines in the drawings show portions of the swing seat with cupholder that form no part of the claimed design. The design shows a single continuous swing seat with cupholder, where the appearance of the article between the zig-zag broken lines forms no part of the claimed design.
